BOX STAYING MACHINE

Charles F. Walz, Philadelphia, Pa., assignor to
 Louis Wolf, Howard A. Wolf, and Elias Wolf,
 copartners trading as National Metal Edge Box
 Company, Philadelphia, Pa.

Application January 30, 1934, Serial No. 708,952

1 Claim. (Cl. 1—12)

This invention relates to a box staying machine and has particular reference to such machine adapted for the application of metal stay strips to the box edges.

5 Machines of the type to which the invention relates are illustrated, for example, in the patents to Stokes, No. 793,549, dated June 27, 1905; Jackson and Horton, No. 1,192,201, dated July 25, 1916, and Walz and Morris, No. 1,346,573, dated July 13, 10 1920. Inasmuch as the general arrangement of parts of such machines is well known, and the present invention relates primarily to details, only so much of the complete machine will be described 15 as is necessary for an understanding of the invention.

In box staying machines of the character referred to, provision is made for the starting of the machine by the depression of a pedal or the like and for the automatic stopping thereof after 20 one revolution if the pedal is released, as in normal operation it should be. If no special provision was made, however, the inertia of the parts even with the pedal released would ordinarily result in a continuance of the operation. To prevent this, there has been used a braking arrangement such as illustrated in the Jackson and Horton patent referred to above, designed to prevent an overrun of the parts of such extent as might 25 initiate another cycle of operation. While such braking arrangement is in general sufficient, its adjustment is somewhat critical, and if the tension is insufficient to produce an objectionable drag of the machine, then there is a danger of overrunning, particularly since the amount of 30 rotation which normally occurs between the stopping position and that which would serve to initiate another cycle is fairly small.

In accordance with the present invention, provision is made to definitely prevent overrun, this 35 taking the form of an arrangement of unyielding character which will definitely bring the parts to rest. It is used, however, in conjunction with the brake heretofore applied so that in general no clashing of the parts to an objectionable degree 40 will result even though the stopping is positive.

Machines of this class have generally been provided with safety stop arrangements which will prevent the die from approaching the anvil if the fingers of an operator or some foreign material is in such position where the normal operation 45 of the die would press it on the anvil. Such safety devices, which are found very satisfactory, are illustrated in the patent to Walz and Morris referred to above, and serve to disengage the die from its operating mechanism in case of

the improper location of the operator's fingers or the like. Such safety device, while it disconnects the positive operating mechanism, does not of itself in its ordinary form prevent the dropping of the cross-head under the action of its own weight. Such dropping of the cross-head is prevented by an adjustment of a suitable gib associated with the cross-head guide so as to engage the cross-head with sufficient friction to prevent such dropping. It is the object of the present 10 invention to provide an improved adjustment of the friction resisting free movement of the cross-head.

The die in machines of this character is provided with a knife fixed thereto and cooperating 15 with a ledger blade formed by the edge of a slot in a cutter slide arranged to reciprocate relatively to the die. Normally this slide is held in a lowered position by the action of springs and as the die descends and approaches the anvil, the 20 strip fed through the slot in the slide is cut off by the descent of the knife relative to the slide which is held against further movement by engagement with the anvil. Heretofore this slide has been mounted to reciprocate vertically in a 25 guideway closed by a plate secured to the end of the die. The securing has been effected heretofore by means of a plurality of screws providing a fine adjustment so to insure a proper cooperation 30 between the knife and the edge of the strip slot. As wear occurs in use, the proper relationship of the cutting parts is not maintained and readjustment must be effected. An arrangement of this sort is illustrated in the Stokes patent 35 mentioned above.

In accordance with the present invention, automatic adjustment is effected by the use of springs which maintain a proper tension, urging the slide just referred to against the knife.

The accomplishment of the objects of the invention will be apparent from the following description read in conjunction with the accompanying drawings, in which:

Fig. 1 is a side elevation of a box staying machine embodying the invention;

Fig. 2 is a fragmentary elevation partly broken away showing means for maintaining a proper relationship between the cutting edges for the staying strip;

Fig. 3 is a front elevation of the same;

Fig. 4 is a fragmentary sectional view showing the improved stopping means;

Fig. 5 is a horizontal section taken on the plane indicated by 5—5 in Fig. 4;

Fig. 6 is a perspective view showing the clutch 55

finger which is arranged to control the clutch key;

Fig. 7 is a sectional view showing the cross-head guideway adjusting means; and

5 Fig. 8 is a vertical section taken on the plane indicated at 8—8 in Fig. 7.

The machine comprises a frame 2 in which is mounted the main shaft 4 having a crank connection with a link 6 which serves to actuate 10 the devices for cutting and handling the stay strip. There are indicated specifically only a few of the parts, for example, the die 8 and the cross-head 60, inasmuch as most of the parts are conventional and well known and are illustrated in the patents referred to above. For 15 example, the safety devices are diagrammatically illustrated, since their specific construction forms no part of the present invention.

Referring particularly to Figs. 1, 4, 5 and 6, 20 there are illustrated therein the parts which control the operation of the main shaft 4. This shaft has keyed thereto the clutch member 10 as indicated at 12, which clutch member is provided with a groove 14 communicating with an 25 opening 16 designed to receive the clutch key 18. This clutch key is adapted to enter openings 20 in the gear 22 under the action of a spring 24. The gear 22 is suitably driven by means such as indicated in the Jackson and Horton patent referred to above. The key 18 is provided with a 30 head 26 which has a cam formed thereon arranged for engagement with a cam 28 formed on a finger 30, which has the form of a bell crank and is connected by a link 32 to a controlling 35 treadle 34, being urged toward position to lift the treadle and stop the machine by a spring 32. If the shaft 4 is rotating and the finger 30 is released so that the cam portion 28 thereof may enter the slot 14, then when the shaft comes 40 around toward its stopping position the cam 28 engages the head 26 of the key 18 and pulls it out of the opening 20 with which it was engaged. In order to stop the machine, there was heretofore provided only a brake arrangement such 45 as indicated at 40, arranged to engage a hub of a disc carried by the shaft 4 with a pressure regulated by the adjustment of the tension of a spring 42. As indicated above, such arrangement was in general satisfactory; but if the 50 tension was insufficient then the inertia of the parts associated with the shaft 4 might be sufficient to carry the clutch member 10 beyond its stopping position so that the key 18 would clear the finger 30 and engage an opening 20 in the 55 gear 22, which is continuously rotated. In such cases, since no box would ordinarily be on the anvil of the machine, successive lengths of stay strip would be fed forwardly, cut off, and pressed upon the anvil, building up a thickness on the 60 anvil which would generally result in breaking the latter after a few revolutions of the shaft 4. The construction heretofore described in connection with the stopping arrangement is old and is illustrated in the Jackson and Horton patent. 65 In accordance with the present invention, positive stopping is insured by the provision of a pin 36 on the clutch member 18 adapted to engage a pin 38 carried by the finger 30 when the finger is in its stopping position. If the tension on 70 the brake 40 is made sufficiently great, contact between the two pins 36 and 38 may be avoided. If, on the other hand, the tension is lessened so as to reduce the drag on the operation of the machine, then the pins 36 and 38 will engage 75 insuring a definite, positive stopping of the shaft

4 at a predetermined point of its cycle of rotation. In general, it is desirable to adjust the spring 42 of the brake 40 so that while the pins 36 and 38 engage, the drag of the brake is sufficient to produce any objectionable knocking; in other words, the shaft is slowed down before the two pins are engaged.

It will be obvious that the construction just described definitely insures against an overrun of the shaft 4 which might serve to initiate successive rotations.

In Figs. 2 and 3, there is illustrated the arrangement for insuring a proper tension upon the slide which provides the ledger blade for cooperation with the strip cutting knife. The die indicated at 8 has secured thereto in the usual fashion the knife 52. The slide 46 is urged downwardly by the springs 48 to a limiting position determined by a stop pin 49 and is furnished with a slot 50 through which the strip passes from the feed and whose lower edge cooperates with the knife in the cutting operation. Heretofore the slide 46 has been held in its guideway in the die 8 by a plate adapted to be finely adjusted inwardly and outwardly. In accordance 20 with the present invention, the plate 54 which holds the slide against the knife is slideable on outwardly extending studs 56 and is pressed inwardly by strong springs 58 reacting between it and the heads of the studs. By a proper choice 25 of the springs 58, a definite tension will be obtained at all times upon the slide irrespective of moderate wear. Adjustment may be provided by arranging the studs so that their heads may be moved inwardly and outwardly; for example, the heads may be threaded on the studs. This, however, is found to be unnecessary, since any wear occurring in use will not permit a 30 sufficient elongation of the springs to appreciably reduce the tension.

The adjustment of the friction on the cross-head is accomplished by the means indicated in Figs. 7 and 8. The cross-head indicated at 60 is provided with bearing surfaces indicated at 62 which cooperate with suitable bearing surfaces 45 supported by an extension 66 of the frame. One of these bearing surfaces is a fixed one indicated at 64. The other has been heretofore provided by means of an adjustable gib similar to that illustrated at 68 but solid in construction. This gib has heretofore been adjusted in the fashion indicated in Figs. 7 and 8, having threaded into it a bolt 70 passing through a transversely elongated slot 72 in the bracket 66. The position of this bolt may be finely adjusted by means of a screw 74 bearing upon it and locked in adjusted position by a nut 76. Adjustment is effected in the present instance and was effected heretofore by a moderate tightening of the bolt 70 followed by an adjustment of the screw 74 which served to move the gib 68 inwardly until a proper friction was observed on the cross-head 60. The bolt 70 was then further tightened and the locknut 76 tightened to hold the screw 74.

In spite of this relatively fine adjustment which was fairly difficult to make, it is obvious that wear on the cross-head would result in a gradual lessening of the friction thereon. The adjustment, moreover, was very critical and very little wear would occasion such complete loss of friction as would permit the cross-head to drop if the safety arrangement disengaged the main driving mechanism therefrom.

To insure a more definite friction upon the cross-head, there is provided in the present in-

stance a plate 78 set into an opening in the inner face of the gib and guided by pins 80 entering slots in the latter. Springs 82 located in sockets in the gib are arranged to press against the plate 78, forcing it against the bearing surface of the cross-head. Adjustment of the springs is effected by rotation of the screws 84, which may be held in adjusted position by lock-nuts 86 and which engage plates 88, serving to back up the springs 82. By the use of this new arrangement, the adjustment heretofore provided becomes no longer critical, the face of the gib itself no longer engaging the bearing face of the cross-head, the bearing being provided by the plate 78. The friction may be adjusted by proper movement of the backing plates 88 of the springs 82. Since the wear results in relatively little elongation of the springs, the tension remaining substantially constant over long

periods, the initial adjustment is readily made and substantially permanently maintained.

It will be clear that variations may be made in details of construction without departing from the spirit of the invention.

What I claim and desire to protect by Letters Patent is:

A box staying machine including stay cutting and fastening mechanism, said cutting mechanism including cooperating cutting elements having a sliding relationship to each other, and means for yieldingly holding said elements in cutting engagement, said means comprising a plate having a substantially fixed relationship relative to one of said elements, and means for yieldingly pressing the plate against the other of said elements to bring the elements together.

CHARLES F. WALZ.
